Primary Examiner — Katrina N Gonzalez(74) *Attorney, Agent, or Firm* — Woodard, Emhardt, Henry, Reeves & Wagner, LLP(57) **CLAIM**

The ornamental design for a hummingbird feeder as shown and described.

DESCRIPTION

FIG. 1 is a perspective view of the hummingbird feeder showing my new design installed on a hat brim with a feeding container installed;

FIG. 2 is a perspective view thereof;

FIG. 3 is a perspective view thereof in a telescoped configuration;

FIG. 4 is a right-side elevational view thereof;

FIG. 5 is a left-side elevational view thereof;

FIG. 6 is a top plan view thereof;

FIG. 7 is a bottom plan view thereof;

FIG. 8 is a back elevational view thereof; and,

FIG. 9 is a front elevational view thereof.

The broken lines illustrate portions of the hummingbird feeder or environmental structure and form no part of the claimed design.

1 Claim, 5 Drawing Sheets(56)
